CLAIM

The ornamental design for a bottle for water dispensers, as shown and described.

DESCRIPTION

FIG. 1 is a perspective view of a bottle for water dispensers according to our design.

FIG. 2 is a front view of the bottle for water dispensers.

FIG. 3 is a left side view of the bottle for water dispensers.

FIG. 4 is a right side view of the bottle for water dispensers.

FIG. 5 is a back view of the bottle for water dispensers.

FIG. 6 is a top view of the bottle for water dispensers; and,

FIG. 7 is a bottom view of the bottle for water dispensers.

The broken lines shown illustrate portions of the bottle for water dispensers and form no part of the claimed design.
